KEY BLANK

Morris Falk, Fitchburg, Mass.

Application January 2, 1934, Serial No. 704,837

3 Claims. (Cl. 76—110)

This invention relates to a special blank from which a finished key is to be made.

The principal object of the invention is to provide a blank of such construction that the cutting of the key will be reduced to its simplest form. This is accomplished by producing a blank with notches in its edge between the points at which the cuts are to be made, leaving only these points projecting so that the key is fitted by cutting each point separately to the proper depth.

Another object of the invention is to provide a blank which can be inserted into the lock before it is cut, thus facilitating in some instances the cutting of the key.

Other objects and advantages of the invention will appear hereinafter.

Reference is to be had to the accompanying drawing, in which

Fig. 1 is a face view of a key blank constructed in accordance with this invention;

Fig. 2 is an end view of the same, and

Fig. 3 is a face view of a second blank also constructed in accordance with this invention.

Owing to the large number of stolen automobiles, pressure has been brought to bear with lock manufacturers to design locks which would be more pick-proof and more resisting to theft. The usual alignment of disc locks in which the tumblers lock on one side and the key combination is cut on one side makes lock picking easy, as well as the reading of combinations because of the one-sided alignment. In order to get away from this some manufacturers have adopted locks of the same type with the tumblers protruding on both sides of the cylinder. This renders the lock more pick-proof and makes the combination more difficult to read.

However, the problem of servicing keys of this type has come about, inasmuch as this is a most difficult type key to duplicate. The combination, instead of being cut on one side in a straight line, must be cut on both sides of the blank, and any inaccuracy either in the blank or in the adjustment of the machine will cause the duplicate key not to operate the lock. The tumblers in locks of this type, and through which the key is supposed to pass, are cut to a certain size much smaller than the actual width of the key itself. It is difficult, therefore, for the locksmith to even try a blank key in the lock before the combination is cut, as the blank key will not enter the lock because the space between the tumblers is narrower than the blank itself.

I have, therefore, designed a special key blank wherein some stock of the blank is already re-

moved, thus allowing the key to enter into the lock and pass through between the tumblers and leaving the full height of the blank on certain points, properly spaced, where the actual tumbler rests and where the actual combination for said tumblers is to be cut. This type of blank eliminates about 75% of the difficulty that locksmiths would have in trying to cut a key either by code or duplication. All that is necessary for the locksmith to do with this type of blank is to cut the proper combination on the points only and the key is then ready to be used.

In the form of the invention shown in Figs. 1 and 2 high portions or projections 10 are provided on each side which extend to the full width 15 of the ordinary blank. Directly opposite each high portion 10 is a side notch 11 providing clearance space to allow the inactive end of the tumbler to pass by it. This renders it possible to have a key made having its projections along 20 opposite sides.

The way in which the key is cut is indicated by dotted lines. Each projection is merely cut off to a certain depth and the whole operation of cutting the key in this case would involve no 25 more than the cutting of these points.

Another feature of the blank as shown is that it is designed for a code having three cuts but in which the first one is always cut away when the blank is made. Therefore it is necessary to cut 30 two depths only on each side to bring the key into proper shape. Therefore, in this case, the first cut on each side is cut or left out of the key blank originally so that no attention has to be paid to these cuts after the key blank is made. 35

In the form shown in Fig. 3 the same principle is shown for a key in which the first cut is not omitted. By supplying a code for the various numbers of depths for each key it is very simple for a locksmith to duplicate or service these keys 40 for his customers. He simply has to cut each projection in accordance with the code.

It will be noticed also that on account of the wide clearance spaces 11 and their alternating with the opposite projections it is possible to 45 insert this key blank into the lock before it is cut. This in some instances aids the locksmith in servicing the key.

Having thus described my invention and the advantages thereof, I do not wish to be limited 50 to the details herein disclosed, otherwise than as set forth in the claims, but what I claim is:

1. A key blank for a tumbler lock having combination levers on opposite sides, the full width of said blank being greater than the space be- 55

5 tween the opposite levers, and alternating pro-
jections and notches along both edges of the
blank, all the projections being located at the
points where cuts have to be made, the notches
on one side registering with the projections on
the other.

10 2. As an article of manufacture, a key blank
provided with uniform high projections widely
spaced apart so that every projection will come
exactly in alignment with a tumbler of the lock
to be fitted, each projection being at least of the
height of the highest combination tumbler of the

lock, whereby said projections can be cut indi-
vidually to the different depths required to fit
the key to the lock.

3. As an article of manufacture, a key blank
having high projections along its opposite edges
with wide clearance spaces between each two
adjacent projections, the projections on one edge
alternating with projections on the other so that
the key blank will not at any point be of full
width, whereby it can be inserted fully into a 10
lock before it is cut.
